UNITED STATES PATENT OFFICE

CLAUDE HAROLD CRAGO, OF STRATHFIELD, NEAR SYDNEY, NEW SOUTH WALES,
AUSTRALIA

GRINDING MILL

Application filed September 24, 1931, Serial No. 564,784, and in Australia January 16, 1931.

This invention relates to grinding mills of the beater type intended primarily for the reduction of cereals and other small gauge materials. The mill consists of an assembly of discs spaced apart on a driving shaft and each armed peripherally with beater blades of rectangular shape held by bolts or rivets passed through cheek rings which are laid onto the sides of the discs. The teeth are fitted in pairs or as twin teeth, one of each pair or one member of each twin tooth offset so as to overhang laterally of the disc. The teeth are sheared from bar steel and they are set into rectangular notches slotted in the rim of the disc. The pairs of teeth are spaced apart symmetrically, the clearance between the adjacent pairs being more or less the length of a tooth. One tooth of each pair is disposed centred, and the others are off-sided left and right in successive order. The mill contains any desired number of discs, usually six to twelve discs being fitted according to the size of the mill; the diameter of the discs may also vary according to the size of the mill.

The beater assembly is set up in a casing, the upper interior portion of which is formed of or is lined with fluted plates or shoes. Preferably these shoes are fitted replaceably in a casing shell. The bottom of the casing is fitted with screens. Only small clearance is allowed between the beater ends and the shoe plates and between the beater ends and the screens. The feed is taken in through a tangential vent in the peripheral wall of the casing. The speed of rotation is variable. In practice a peripheral speed of twelve thousand to fourteen thousand feet per minute is found to give satisfactory results. The milled product passes out through the screens in the bottom of the casing; the material which remains in the casing is churned and submitted to repeated batterings by the beaters and against the inner faces of the shoes until it is reduced in gauge sufficiently to allow it to pass through the screens.

Provisions of exhaust means for removing air borne material from the casing is optional.

Doubling of the length of service of the

beater assembly is obtainable by making it reversible, that is to say, fitting the beaters so that they can be turned end-for-end thus to bring the unworn back faces of the beaters into the active position after their front faces are worn in service.

To assist in keeping down temperature in the mill, the driving pulley may be filled with propeller blade spokes to operate as air impellers and vents are provided through the casing ends to admit air blasts produced by these impellers.

In the accompanying drawing:—

Fig. 1 is a transverse vertical section through the mill;

Fig. 2 a fragmentary cross section;

Fig. 3 a fragmentary elevational view illustrating one of the air inway valved ports in the end covers of the mill casing; and

Fig. 4 is a fragmentary view showing the method of forming twin teeth on a double width blank.

The casing comprises end covers 1 and 2, an upper section longitudinally fluted as shown at 3 and having a gravity feed pipe 4 entering it tangentially, and a lower open frame section in two quadrant parts 5 and 6 both fitted with gauze screens 7. A monitor casing 8 houses the lower section 5-6 and supports the upper section 3. 9 are lugs in the top part of the monitor 8 with centring dowel screw pins 10 tapped through them for supporting the top ends of the quadrant frames 5 and 6; the bottom ends of these quadrant frames seat on a bearer 11. 12 is a conveyor screw in a troughway 13 in the bottom of the monitor 8, for removing milled product which has been delivered through the screens 7. 14 are access doors. 15 are air ports in the end covers 1 and 2, 16 are slide dampers for regulating the area of these ports, and 17 are air hoods which house and protect the dampers and direct air draft inward to the dampered ports.

The upper section 3 may be constructed as a shell fitted interiorly with demountable shoe plates. The liner or shoe plates are fluted as shown in Fig. 1. The flutes should be unsymmetrical in cross section, the deepest

part of each concavity being at the leaving end.

The beater assembly consists of a group of steel discs 20 set up concentrically and spaced apart on a shaft 21 with beater blades 22-23 demountably fixed in their peripheries. The invention consists in the particular means by which the beater blades 22-23 are fixed in the discs 20. The discs 20 are spaced apart on the shaft 21 between thimbles 24, 25 being check pins on the outermost thimbles and 26 a key. 27 are the shaft bearings and 28 a driving pulley. The air damper 16 is a slotted plate slidably fitted over the air vent 15 in the air shield 17, and provided with an operating lever 32 moving over a check quadrant 33.

The beater blades 22-23 are sheared from steel bars and as shown in Fig. 1 are fixed in pairs in rectangular notches cut at spacings symmetrically apart in the disc peripheries. One blade 22 of each pair is a straight blade and is disposed in plane with the disc and the other blade 23 of the pair is offset by bending it laterally so that its tip overhangs the interblade space. The blades 23 are offset alternately right hand and left hand. The butt of each blade is holed and check rings 36 are riveted (37) one on each side of each disc, these rings being of the same diameter externally as the discs. The blades 22-23 are demountably fixed in the notches in the disc peripheries by bolts or rivets 38 which pass through holes in both cheek rings 36 and through the holes in the blade butts. When the beater blades 22-23 are worn on the leading edges the bolts or rivets 38 are drawn and the blades reversed and re-fixed. Both edges of the blades are thus utilized. The same result is obtainable by reversing the whole beater assembly end-for-end. The angle of offset should be sufficient to bring the tips of the offset blades on one disc near to the tips of the offset blades in the adjacent disc. It is thus ensured that the feed will not pass between the discs without suffering reduction by contact of the offset blades with it.

Only small clearance is allowed between the blade tips and the ridges of the flutings in the top section of the casing and between the blade tips and the inner face of the gauze screens.

The material required to be milled is supplied by gravity through the feed pipe 4. On entering the casing it is struck by the beaters and whirled and thrown against the fluted shoes and swirled over the screens. The screens pass the fine gauze material whilst the coarser gauze stuff is subjected to repeated beating and battering until it is reduced sufficiently to pass through the screens.

Fig. 4 shows a twin blade formed by splitting a double width beater blank for portion

of its length and offsetting one of the split ends; when this form of construction is used one bolt 38 suffices to hold the butt of the pair tooth in the notch in the disc.

What I claim as my invention and desire to secure by Letters Patent is:—

1. In a beater mill of the kind herein described, a cylindrical chamber, an assembly of discs with notches of rectangular shape cut toothwise in their peripheries, said discs being spaced apart on a driving shaft within said chamber and the diameter of said discs being slightly less than the diameter of the chamber, a pair of cheek rings fixed at opposite sides of each disc near its periphery, and a plurality of short rectangular shaped beater blades set in said notches in the plane of the disc and fixed by bolts or rivets passed through their butts and through the cheek rings. 75

2. A beater mill according to claim 1 having the beater blades fitted as twins or in pairs, one blade of each twin or pair offset laterally and the offset blades alternated left and right respectively. 80

In testimony whereof I affix my signature,

CLAUDE HAROLD CRAGO.
